CONVERTIBLE RECLINING CHAIR

Elihu T. Paul, Corbin, Ky., assignor of one-half
to Frank Craft, Pikesville, Ky.

Application February 19, 1943, Serial No. 476,432

3 Claims. (Cl. 155—106)

This invention relates to chairs and more particularly to convertible reclining chairs and it consists in the constructions, arrangements and combinations herein described and claimed.

It is an object of the invention to provide a convertible reclining chair having a perfect balance, requiring a minimum of effort on the part of the occupant to move the seat and back rest from a normal position to a reclining position and vice versa.

It is also an object of the invention to provide novel stop means for limiting movements beyond the proper reclining position of the seat and back rest, as well as stop means for the normal position of the chair.

It is a still further object of the invention to provide a novel construction and mounting of a foot rest whereby strain on the pivots of the chair is eliminated, specially when a person gets into or out of the chair.

Additional objects, advantages and features of invention will be apparent from the following description and accompanying drawing, wherein,

Figure 1 is a side elevation of a chair constructed in accordance with the invention, with a portion of the supporting frame broken away.

Figure 2 is a front elevation thereof,

Figure 3 is a top plan view thereof,

Figure 4 is a cross section on the line 4—4 of Figure 1,

Figure 5 is a side elevation of the chair, parts being broken away, illustrating the reclining position of the chair.

There is illustrated a chair generally indicated by the reference character 10 consisting of a pair of side frame members 11, shown in the present instance as an inverted U-shaped frame 12, between the legs 13 of which there is secured a side wall 14. The frame members 11 may be constructed from wood, metal or other suitable material, as found practical. The frame members 11 are suitable spaced apart and rigidly connected by a panel 15 at the rear, the panel stopping short of the upper edges of the frame members in order to provide a clearance for swinging movements of the back rest presently to be described.

A combined seat and back rest 16 is employed, of an overall width such as to freely fit between the frame members 11. The seat is indicated at 17 and consists of a base frame 18 upon which there is suitably constructed an upholstered cushion. The back rest consists of a base 19 suitably upholstered to afford comfort to an occupant. The lower edge of the back rest is piv-

otally connected to the rear edge of the seat as indicated at 20, the seat and rest being suspended within the chair frame in such relation as to afford the greatest comfort to an occupant, as will now be explained.

Inwardly of the front legs 13 of the side frame 11, a front hanger bar 21 is pivotally mounted at its upper end upon a pivot pin 22 fixed within the side walls 14, the lower end of the hanger bar 21 being pivotally connected as at 21' to a side rail 23 of a foot rest 24. The hanger bars 21 lie outwardly of the side rails and flush against the sides of the base frame 18 of the seat and at a point adjacent the upper edge of the base 15 frame, the hanger bars are pivoted thereto, as indicated at 25.

Forwardly of the rear legs 13 of the side frame 11, pins 26 are provided for pivotal mounting of rear hanger bars 27. The hanger bars 27 lie flush with the frame 19 of the back rest and are pivotally connected adjacent the upper ends thereof as indicated at 28. The rear hanger bars 27 are of a length stopping slightly above the supporting surface of the legs 13, for pivotally mounting the rear ends of the side rails 23, as shown at 29. The bars 27 extend above the pivot pins 26 a substantial distance.

Upon the forward underside of the seat frame 18 a stop 30 is secured, which functions to limit the reclining position of the chair, and upon each side frame 11 a stop 31 is secured upon respective walls 14 for limiting backward swinging movement of the front hanger bars, the movement of which is also prevented by contact of the foot rest 24 upon a supporting surface, such as the floor.

The hanger bars 21 are pivotally connected to the side walls 14 and related to the seat 17 and the side rails 23 so as to form, substantially, a parallelogram, the pivotal points of which are so located as to present a perfect balance of the seat and back-rest, necessitating a minimum of effort to convert the chair into a reclining position and without sudden or abrupt movements when returning to normal position of the chair.

In use, a person enters the chair by stepping directly upon the foot rest 24 and seats himself upon the seat 17. Since the foot rest engages the floor, strain upon the pivots is avoided. Now when it is desired to attain a reclining position of the chair, a backward pressure is exerted upon the back-rest, which may be accomplished by the mere backward movement of the head, augmented by a slight forward exertion upon the foot rest. As soon as the chair has reached

the full reclining position, as shown in Figure 5, the stop 30 will engage respective side rails 23 and further movement will be prevented. It will be noted that in the full reclining position of the chair, the seat 17 moved in a forward direction and slightly upward and the rear hanger bars 27 and the side rails 23 were similarly moved, so that the axis of the hinge 20 of the seat and back rest is positioned at a point substantially in the longitudinal axis of the rear hanger bars. In this position of the parts, the body of the person is properly balanced upon the seat and back rest so as to maintain such reclining position without effort. To bring the chair to normal position, it is only necessary for the person to move his head forwardly slightly when an overbalance of the hanger bars, side rails and foot rest is accomplished and downward rearward movement of the seat and back rest is attained in a slow easy manner, until the foot rest engages the floor and the front hanger bars 21 engage the stops 31.

While I have shown and described a preferred construction, this is by way of illustration only, and I consider as my own all such modifications in construction as fairly fall within the scope of the appended claims.

I claim:

1. A convertible reclining chair comprising parallel side frame members connected in spaced relation, a rear hanger bar pivotally connected to rear upper portions of each frame member, a back rest pivotally connected to upper portions of the hanger bars, respective front hanger bars pivotally mounted adjacent the upper front portion of the frame members, a seat member hingedly connected to a lower portion of the back rest and pivotally connected between respective front hanger bars adjacent the upper ends thereof, a side stringer member pivotally connected to the lower extremities of said back and front hanger bars, stop means engageable with the front

hanger bars for limiting backward movement thereof and stop means carried by the seat and engageable by said side stringer members for limiting the reclining position of the back rest and said seat.

2. A convertible reclining chair comprising parallel side frame members connected in spaced relation, a rear hanger bar pivotally connected to the rear upper portions of each frame member, a back rest pivotally connected to upper portions of the hanger bars, respective front hanger bars pivotally mounted adjacent the upper front portion of the frame members, the downward length of the front and rear hanger bars from their points of pivot being such as to stop closely adjacent the supporting surfaces of the side frame members, a side stringer member being pivotally connected between respective front and rear hanger bars, a foot rest connecting the side stringer members and located forwardly of the frame members, said foot rest being adapted to contact a supporting surface in normal position of the stringer members, a stop means on respective frame members in the path of rearward swinging movement of the front hanger bars, a seat member pivotally connected to the lower portion of the back rest member and to respective front hanger members below the pivotal mountings thereof and a stop member on the lower front portion of the seat for contacting engagement with respective side stringer members for limiting reclining position of the back rest and said seat.

3. The structure of claim 2 in which the pivots of said hanger bars are so located with respect to the pivotal connection between the back rest and seat that in the reclining position of the latter, the pivot between the back rest and seat will lie in a plane substantially in the medial longitudinal axis of the rear hanger bars.

ELIHU T. PAUL.
